L. L. WHITNEY,
METHOD OF FORGING STEEL FULCRUMS.
APPLICATION FILED NOV. 30, 1917.

UNITED STATES PATENT OFFICE.

LOREN L. WHITNEY, OF HAMMOND, INDIANA, ASSIGNOR TO AMERICAN STEEL
FOUNDRIES, OF CHICAGO, ILLINOIS, A CORPORATION OF NEW JERSEY.

METHOD OF FORGING STEEL FULCRUMS.

1,280,606.

Specification of Letters Patent.

Patented Oct. 1, 1918.

Application filed November 30, 1917. Serial No. 204,572.

To all whom it may concern:

Be it known that I, LOREN L. WHITNEY, a citizen of the United States, and resident of Hammond, in the county of Lake and 5 State of Indiana, have invented certain new and useful Improvements in Methods of Forging Steel Fulcrums, of which the following is a specification.

This invention relates to a method of 10 forming brake beam fulcrums with an integral third point support.

The object of the invention is to improve and simplify the method of forging brake beam fulcrums having an integral 15 third point support.

Generally speaking, this object is accomplished by use of the method of forming a brake beam fulcrum consisting first in providing a blank having two spaced portions, 20 then inserting another blank between said spaced portions and in contact therewith, and then upsetting the two blanks to form a seat on one of the blanks and a third point support on the other of said blanks.

25 The method is illustrated on the accompanying sheet of drawings, in which—

Figure 1 is a plan view of a piece of stock which forms one of the blanks;

Fig. 2 is a plan view, and Fig. 3 is a side 30 elevation of the blank after one end thereof has been twisted and a portion thereof deflected;

Fig. 4 is a plan view, and Fig. 5 is a side 35 elevation of the same blank after the other end has been treated in a similar manner;

Fig. 6 shows the blank after being bent to form a loop or bent into a position whereby two of its portions are parallel 40 with each other and connected to form a closed end;

Fig. 7 is a view showing a second blank inserted into the end of the loop of the first blank;

Fig. 8 shows a completed fulcrum where- 45 in the first blank is provided with a seat and a third point support is formed from the metal of the second blank; and

Fig. 9 is an end view of the completed 50 brake beam fulcrum.

55 The various novel features will be apparent from the following description and drawings and will be particularly pointed out in the appended claims.

There are various methods of forming 55 brake beam fulcrums. Most of such meth-

ods, however, are more or less complicated, and do not furnish a finished product adapted to meet all of the requirements for successful commercial operation.

In my improved method I make use of 60 two blanks 10 and 11. The first one is of flat metal stock, and the second preferably is in the form of a cylinder. In shaping the first blank, one end 12 first is 65 twisted a given amount and a portion 13 thereof deflected laterally. The other end of the blank 10 then is treated in the same manner to provide an angularly arranged portion 14 and a deflected portion 15. The blank 10 then is bent intermediate its ends 70 and preferably at the middle portion to form a loop or opening 16, as shown in Fig. 6, the loop being formed by two preferably parallel spaced portions or members 17, the loop 16 being closed at one end preferably 75 by a curved wall 18. The front end of the loop or opening 16 thus formed receives the second blank, which is placed between the side wall portions 17, and also placed in engagement therewith and in engagement with the curved end wall 18 of the loop or opening 16. It will be understood 80 that at the time the second blank 11 is inserted into the first blank, as shown in Fig. 7, the second blank 11 and the coöperating end portion of the first blank, will be at welding heat, or they may be placed together prior to the time that they are heated and then brought to welding heat together. These blanks are then secured in proper 85 dies and upset to form a seat 19 in the metal formed by the first or large blank 10, and to form a third point support 20 from the metal of the second blank 11, it being understood that the finished product shown 90 in Figs. 8 and 9 is an integral structure. The seat 19 is for the reception of the tension member of a brake beam, and the laterally extending portions 13 and 15 at the other end of the fulcrum are to be 95 secured to the compression member of the brake beam.

By means of this method integral brake beam fulcrums may be provided in a very simple manner and at the same time meet 105 the various requirements for successful commercial operation.

I claim:

1. The method of forming a brake beam 110 fulcrum consisting first in providing a blank

in the form of a loop, then inserting another blank within the loop of the first blank, and then upsetting the two blanks to form an integral structure with a seat and a third point support.

2. The method of forming a brake beam fulcrum consisting first in providing a blank in the form of a loop, then inserting another blank within the loop of the first blank, and then upsetting the two blanks to form an integral structure with a seat in the first blank and a third point support formed from the second blank.

3. The method of forming a brake beam fulcrum consisting first in providing a blank in the form of a loop, then inserting another blank within the loop in contact with the first blank, and then upsetting the two blanks to form an integral structure with a seat in one blank and a third point support formed from the other blank.

4. The method of forming a brake beam fulcrum consisting first in providing a blank having two spaced members, then inserting another blank between said members in contact therewith, and then upsetting said blanks to form an integral structure in which a seat is formed in one of said blanks and a third point support from the other of said blanks.

5. The method of forming a brake beam

fulcrum consisting first in providing a blank having a closed end, then inserting a second blank in said closed end in contact with the first blank, and then upsetting said blank to form an integral structure in which a seat is formed in one of said blanks and a third point support from the other of said blanks.

6. The method of forming a brake beam fulcrum consisting first in providing a blank with an opening therein, then inserting a second blank in said opening in contact with the first blank, and then upsetting said blanks to form an integral structure in which a seat is formed in one of said blanks and a third point support from the other of said blanks.

7. The method of forming a brake beam fulcrum consisting first in providing a straight blank, then bending the same, then placing a second blank in the bend and in contact with the first blank, and then upsetting said blanks to form an integral structure in which a seat is formed in one of said blanks and a third point support from the other of said blanks.

Signed at Hammond, Indiana, this 19th day of November, A. D. 1917.

LOREN L. WHITNEY.
